UNITED STATES PATENT OFFICE.

FRANK HERBERT FOSTER, OF HONOLULU, HAWAII.

DESIGN FOR A HOE.

SPECIFICATION forming part of Design No. 28,429, dated March 29, 1898.

Application filed February 8, 1898. Serial No. 669,593. Term of patent 14 years.

To all whom it may concern:

Be it known that I, FRANK HERBERT FOSTER, of Honolulu, Hawaii, have invented and produced a new and original Design for a 5 Sugar-Planter's Hoe, of which the following is a full, clear, and exact description.

Reference is to be had to the accompanying drawings, forming a part of this specification, in which—

- o Figure 1 is a perspective view of a sugar-planter's hoe embodying my new design, and Fig. 2 is a transverse section thereof on the line 2 2 in Fig. 1.

The design in its entirety comprises a blade 5 of increasing width from top toward the bottom, the side edges from the rear to a point terminating at a distance short of the front edge presenting series of elongated teeth and the blade in front of the said teeth being

plain and untoothed, the untoothed side portions being approximately in line with the teeth. Further, in the blade adjacent to the upper edge in the center is an orifice surrounding which is a forwardly-projecting annular flange or neck. 20 25

The leading feature of the design resides in the blade presenting elongated teeth at the side edges from the rear to a point short of the front, the blade in front of the teeth presenting a broad surface with untoothed side 30 edges.

I claim—

The design for a sugar-planter's hoe herein shown and described.

FRANK HERBERT FOSTER.
